UNITED STATES PATENT OFFICE.

CLARENCE MILES BURNAM, OF CHICAGO, ILLINOIS, ASSIGNOR OF ONE-HALF
TO JACOB HEINSFURTER, OF CHICAGO, ILLINOIS.

GOLF-CLUB.

SPECIFICATION forming part of Letters Patent No. 727,086, dated May 5, 1903.

Application filed May 26, 1902. Serial No. 109,084. (No model.)

To all whom it may concern:

Be it known that I, CLARENCE MILES BURNAM, a citizen of the United States, residing at Chicago, in the county of Cook and State 5 of Illinois, have invented certain new and useful improvements in Golf-Clubs, of which the following is a specification.

In playing the game of golf it is necessary to use a number of clubs the faces of which 10 are made to incline at different angles with relation to the center line of the shaft. These different-angled clubs are necessitated by the lie of the ball on the ground and the condition of the ground when the stroke is made 15 and the distance of the ball from the hole. These clubs are so expensive and so many are needed that it does not permit the people of the medium classes to enjoy the game on account of the expense. In addition to this 20 a person wishing to play is compelled either to carry all of these clubs while playing the game, thus making work of a pleasure, or else to employ some one else to carry the clubs, thus incurring additional expense. My invention 25 is designed to remedy this state of affairs and to make a club which will be capable of a quick adjustment, yet not differing materially in appearance from the club now in use, and which can be adjusted not 30 only as to the angle of the face in relation to the center line of the shaft, but to also have an adjustment in the handle allowing one to readily shorten or lengthen the length of the shaft, so as to conform with the length of the 35 handle of the different clubs.

The principal object of my invention is to construct a club which to all effects and purposes is capable of use in the place of any one or all of the iron or brass clubs now used 40 or needed, it not being intended to be used as a substitute for the wooden clubs.

My club can at the same time be manufactured inexpensively, with an adjustment both in the head and handle which can not only be 45 easily and quickly adjusted, but which will when adjusted possess all of the rigidity of the non-adjustable club and which will not loosen in use.

My method in accomplishing these objects

is shown in the annexed drawings, which are 50 a part of this specification, and in which—

Figure 1 is a rear view of the entire club. Fig. 2 is an enlarged detail view, partly in section, showing the method of adjusting the head or blade. Fig. 3 is a cross-sectional 55 view taken on the line X X of Fig. 2. Fig. 4 is a detail view, partly in section, of the handle and clamp for same.

Similar letters refer to similar parts throughout the several views.

Fig. 1 is a rear view showing the entire club, in which A is the shaft, extending at its upper end into a tubular handle *a* and its lower end fitting into a socket *b*, formed by part of the head. It is secured in place in the 65 usual manner. This part *b* of the head has a face *b'* at its lower end, with ratchet-teeth cut thereon. Extending from the center of the ratchet is a steel rod *b*², which is threaded into the socket, and its end *b*⁷ is then peened or 70 riveted over very securely, thus effectually preventing its loosening under any conditions which could possibly arise in playing the game, or the socket and rod may be forged integral. The other end of the steel rod *b*² is 75 threaded and has mounted upon it a cap-nut *b*⁶, having annular openings in it to permit of its being tightened and loosened with a spanner-wrench, a blade *b*⁴ having a rib *b*⁵ on its back, which rib has an annular opening 80 therein and ratchet-teeth cut upon its end face to coincide with the teeth cut upon the face *b'* upon the socket part of the head *b*. This blade *b*⁴ is mounted upon the rod *b*², which extends through the annular opening 85 in the rib *b*⁵ upon the back of the blade *b*⁴, and when the cap-nut *b*⁶, which is threaded upon the end of the rod *b*², is tightened it draws the teeth of the blade *b*⁴ and the socket *b'* so that they engage, and the entire head 90 becomes as rigid and firm as if it was one piece, the head of the club then presenting to view a smooth finished surface, its face not differing from the non-adjustable clubs and its back not differing materially from the numerous clubs having weights on the back of the blade.

When it is desired to alter the angle, the

face of the blade b^4 , the cap-nut b^6 is loosened. The teeth of the ratchet on the rib b^5 being released from engagement with the teeth of the ratchet on the socket b' , it becomes possible to turn the blade b^4 upon the rod b^2 and place it at any angle in relation to the line of the shaft which is desired or called for by the position of the ball. When it is in the position desired, the cap-nut b^6 is then tightened and the blade locked in the desired position.

Fig. 4 shows an enlarged detail view, partly in section, of the handle, in which A is a shaft which extends into a tubular handle a . The lower end a' of this handle a is slotted and the outer surface slightly tapered. A thread is cut upon the tapered portion thereof. Mounted upon this tapered portion is a shell or sleeve a^3 , having its inner surface tapered to coincide with the tapered portion of the handle a and having internal threads cut thereon to match with the thread a^2 cut upon the tapered portion a' of the handle a , so that a very slight twist of this sleeve or shell a^3 is sufficient to clamp the shaft A very firmly, owing to the extended bearing-surface of the interior of the tubular handle a upon the shaft A . By loosening the shell or sleeve a^3 the shaft A can either be pushed up into the tubular handle a or withdrawn from it, thus shortening or lengthening the shaft, as is desired. The upper part of the tubular handle a carries a wooden plug, which serves as a handle for a spanner-wrench used to adjust just the cap-nut b^6 .

My club possesses another qualification which makes it very desirable, which is that it is at all times the same weight, so that one is enabled to play with greater skill by becoming accustomed to one club instead of having to change frequently from one to another, this necessitating becoming used to each different club before being able to use it with the same degree of skill.

45 What I regard as new, and desire to secure by Letters Patent, is—

1. In a golf-club the combination of a shaft, a tubular handle mounted thereon; having its lower end tapered; threads cut upon said tapered portion and an internally-threaded sleeve mounted thereon, the lower end of the shaft having a metal socket attached thereto, the metal socket being bent to one side, giving an appearance somewhat similar to a gooseneck and terminating in a hemispherical-shaped end having ratchet-teeth cut upon the flat face thereof and a rod extending from the center of said flat face and a blade mounted upon said rod with teeth cut upon one end thereof to coincide with the teeth cut on the socket and means for securing the blade in position.

2. In a golf-club, the combination of a shaft, a tubular handle mounted thereon, having its lower end tapered, threads cut upon said tapered portion, an internally-threaded sleeve

mounted thereon, a socket-head mounted upon the lower end of the shaft, means for securing the socket-head to the shaft, said socket being bent to one side presenting an appearance somewhat similar to a gooseneck and terminating in a hemispherical-shaped end having ratchet-teeth cut upon the flat face thereof and a rod extending from the center of said flat face, said rod and said socket being made integral; a blade having ratchet-teeth cut upon its end face mounted and turning upon the rod, means for securing the blade in position, for the purpose set forth substantially as described.

3. In a golf-club the combination of a shaft, a tubular handle mounted thereon, having its lower end tapered, and slotted threads cut upon said tapered portion, an internally-threaded sleeve fitting to and coinciding with the threads cut upon the tapered portion of the said tubular handle, a spanner-wrench having a wooden plug for its handle, said wooden plug being mounted in the upper end of the said tubular handle and serving as a cap therefor, the lower end of the shaft having a metal socket attached thereto, the metal socket being bent to one side giving an appearance somewhat similar to a gooseneck, said socket terminating in a hemispherical-shaped end having ratchet-teeth cut upon the flat face thereof, and a rod extending from the center of said flat face, and a blade mounted upon said rod, the blade having one side smooth, the other side having a tubular rib extending transversely upon it, and at the outer end a chambered recess, the inner end of the rib having a shoulder thereon, the periphery of said shoulder meeting the smooth side of the blade, a recess cut upon the inner surface of said shoulder and ratchet-teeth cut upon the end of the rib connecting with the teeth cut upon the socket, means to hold said teeth in engagement, for the purpose set forth substantially as described.

4. In a golf-club, the combination of a shaft, a tubular handle mounted on its upper end, the lower end of said tubular handle being tapered and slotted, threads cut upon said tapered portion, an internally-threaded sleeve fitting to and coinciding with the threads cut upon the tapered portion of said tubular handle, attached to the lower end of the shaft a metal socket, the metal socket being bent to one side presenting an appearance somewhat similar to a gooseneck, said socket terminating in a hemispherical-shaped end, having a threaded hole in the center of the flat side and ratchet-teeth cut upon the flat face, a rod mounted in said hole, means for securing said rod in position, a shoulder on said rod, the end of the rod being reduced and a thread cut thereon, a blade mounted on said rod, the blade having one side smooth, the other side having a tubular rib extending transversely upon it, and at the outer end of the rib a chambered recess, the inner end of the rib

having a shoulder thereon, the periphery of | and hold said blade in position, for the pur-
said shoulder meeting the smooth side of the | pose set forth substantially as described.
blade, a recess cut upon the inner surface of |
said shoulder and ratchet-teeth cut upon the |
5 end of the rib connecting with the teeth cut |
upon the socket, a nut mounted upon the |
thread on the reduced end of the rod to secure |
